DRESS ENSEMBLE

Elizabeth Cutler, New York, N. Y.

Application August 5, 1950, Serial No. 11,620

Term of patent 3½ years

(Cl. D3—26)

To all whom it may concern:

Be it known that I, Elizabeth Cutler, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is a front view of a dress ensemble, showing my design.

Fig. 2 is a fragmentary rear view thereof,

Fig. 3 is a fragmentary front view of the dress member of the dress ensemble on a reduced scale, and

Fig. 4 is the rear view thereof.

I claim:

The ornamental design for a dress ensemble, substantially as shown.

ELIZABETH CUTLER.
